UNITED STATES PATENT OFFICE.

JOHN G. FURLOW, OF PHILADELPHIA, PENNSYLVANIA.

DESIGN FOR A DRAIN-PIPE.

SPECIFICATION forming part of Design No. 30,318, dated March 7, 1899.

Application filed January 26, 1899. Serial No. 703,513. Term of patent 7 years.

To all whom it may concern:

Be it known that I, JOHN G. FURLOW, a citizen of the United States, residing in Philadelphia, Pennsylvania, have invented a certain new and useful Design for a Drain-Pipe, of which the following is a specification.

My design for a drain-pipe is clearly illustrated in the accompanying drawing, the figure of which represents my new design in perspective.

The essential feature of the design is the T-section having two short extensions and one long extension.

A is the drain-pipe, having an enlargement A'. Projecting from one end of this enlargement is a short cylindrical extension b, and

projecting from the opposite end is a long cylindrical extension d, and projecting from the side of the enlargement and at right angles to the extensions b and d is a short cylindrical extension a, having a flange.

I claim—

The design for a drain-pipe, as herein described and as shown in the accompanying drawing.

In testimony whereof I have signed my name to this specification in the presence of two subscribing witnesses.

JOHN G. FURLOW.
